UNITED STATES PATENT OFFICE.

HARRISON WOODMANSE, OF FREEPORT, ILLINOIS.

TIGHTENER FOR BRACE-RODS.

SPECIFICATION forming part of Letters Patent No. 609,865, dated August 30, 1898.

Application filed May 19, 1898. Serial No. 681,165. (No model.)

To all whom it may concern:

Be it known that I, HARRISON WOODMANSE, a citizen of the United States, residing at Freeport, in the county of Stephenson and State of Illinois, have invented certain new and useful Improvements in Tighteners for Brace-Rods, of which the following is a specification.

The object of this invention is to provide means for tightening diagonal braces—as, for instance, the cross-braces in windmill-towers, to which this invention particularly applies.

In the accompanying drawings, Figure 1 is an elevation of this tightener in position upon the diagonal braces of a windmill-tower. Fig. 2 is a perspective view of the principal member of the tightener-clamp, showing the position which the brace-rods occupy therein. Fig. 3 is a face view of the same; and Fig. 4 is a longitudinal central section thereof on dotted line $\alpha\alpha$, Fig. 1.

Like letters of reference indicate corresponding parts throughout the several views.

A are the vertical members of a windmill-tower.

B are cross-bars extending between and secured rigidly to the vertical members A.

C are the diagonal brace-rods of the tower.

D is the principal member of the tightener-clamp. It is provided with the raised portions D' and D'' at either side thereof and the like projection D³ near one end of the said member D. It also has the central opening D⁴ for receiving the clamping-bolt, the serrations D⁵, and the extending wire loop D⁶, formed by placing the said loop in the mold and pouring the fluid metal which is to form the member D around the ends of said loop.

E is the upper clamping member, of circular form, having the impinging edges E' for bearing upon the brace-rods C when the clamp is in operative position.

F is the clamping-bolt, which firmly binds together the members D and E.

G is a bolt extending through the loop D⁶ for holding the latter firmly in contact with the cross-bar B. In application the member D of this tightener is placed on the brace-rods C at their point of crossing in the manner shown in Fig. 2. The upper member E is put in position and the clamping-bolt F inserted through the openings provided to re-

ceive it. The bolt G is put through the loop D⁶ and the whole tightener drawn or driven downward until the brace-rods C are bent sufficiently from a straight line to make them 55 taut. The bolt G is then drawn tight upon the loop D⁶, and the members D and E of the tightener are clamped firmly together by the bolt F.

Should the brace-rods C at any time become loose, the bolts F and G may be loosened and the rods tightened, as before.

I claim as my invention—

1. In a tightener for brace-rods, in combination, a clamp comprising two disk-like 65 members, means for holding the members together and a projection extending from one of the members for securing the clamp to the framework, substantially as and for the purpose specified.

2. In a tightener for brace-rods, in combination, a clamp comprising two disk-like members, one of said members having a projection for the reception of the brace-rods and a serrated surface for preventing the 75 slipping of the clamp with relation to the rods, a bolt for holding the members together and a projection from one of the said members for securing the clamp to the framework, substantially as and for the purpose specified. 80

3. In a tightener for brace-rods, in combination, a clamp comprising two members, one of said members having a projection providing for the reception of the brace-rods and a serrated portion for preventing the slipping 85 of the clamp with relation to the rods, means for holding the members together and a loop extending from one of the members of the clamp for securing the latter to the framework, substantially as and for the purpose 90 specified.

4. In a tightener for brace-rods, in combination, a clamp comprising two members, one of said members having three projections providing for the reception of the brace-rods and 95 a serrated portion for preventing the slipping of the clamp with relation to the rods and means for holding the members together, substantially as and for the purpose specified.

5. In a tightener for brace-rods, in combination, a clamp comprising two members, one of said members having three projections pro-

viding for the reception of the brace-rods and a serrated portion for preventing the slipping of the clamp with relation to the rods, the other one of said members having an edge 5 adapted to impinge upon one of the rods, means for holding the members together and a loop extending from one of the members of

the clamp for securing the latter to the framework, substantially as and for the purpose specified.

HARRISON WOODMANSE.
